UNITED STATES PATENT OFFICE.

FREDRICK H. AULD, OF COLUMBUS, OHIO, ASSIGNOR TO THE D. L. AULD COMPANY, OF COLUMBUS, OHIO, A CORPORATION OF OHIO.

SIGN.

Application filed December 7, 1925. Serial No. 73,714.

This invention relates to an improved article comprising a reading sign and to a method of producing such sign.

The article comprising the sign consists, essentially, of a back plate of metal fashioned, as by a die or otherwise, with a deeper depression and a shallow depression, the deeper depression to receive an adhesive material and a series of individual blocks each containing at least one letter, number or other indicia, the blocks being adapted to occupy any position in this deeper depression so as to be properly distributed to cause the whole series of blocks to present their letters, numbers or other indicia in readable order; and the shallow depression to also receive adhesive material, and the deeper recess and the spaces surrounding the letters, numbers or indicia, as also the shallow depression, all to receive a veneer of wood which when finished will constitute an ornamental field within which will appear the readable matter.

The method branch of my invention consists, essentially, in the steps of fabricating the base plate with deeper and shallower depressions; in fabricating the separate blocks each with at least one letter, number or other indicia; in overlaying said deeper depressions with an adhesive material, preferably dissolved or dissolvable celluloid; in positioning the indicia blocks one after another in the deeper depression to constitute of the whole the readable matter; in applying an adhesive material, also preferably dissolved or dissolvable celluloid over and upon the letters, numbers or indicia and over and upon the shallower depressions; in overlaying the face of the article so far built up with a thin veneer of ornamental wood, also preferably coated or saturated on one side with an adhesive material, preferably dissolved or dissolvable celluloid; in subjecting the whole to high pressure to cause the wood veneer to enter and fill the shallower depression and the depressed surfaces all about and within the letters, numbers or other indicia; in preferably accompanying such pressure with the application of heat to more effectively cause the adhesive to unite with the wood veneer; and in dressing off or removing the surplus or shattered wood to leave the depressions filled and the face of the letters, numbers or indicia ex-

posed and in a polished state; the pressure 55 instrumentality contacting with the wood veneer having a flat pressure surface to depress the veneer into the recesses and shatter the parts above the raised surfaces.

In the accompanying drawings:— 60

Figure 1 is a plan view of a metal back plate with the deeper and shallower depressions and the border showing also the adhesive applied to the deeper depression and the individual letter blocks positioned in 65 such depression;

Figure 2 is a front view of the finished product with its exposed letters and surrounding inlaid field of ornamental veneer;

Figure 3 is an enlarged longitudinal vertical sectional view of the plate shown in Figure 1 with the coating of adhesive material above the letters and over the shallower depressions, and with a sheet of veneer overlying the whole; 75

Figure 4 is a like view showing the condition after the steps of pressure and heat and ready for the step of dressing-off;

Figure 5 is a similar sectional view of the wood veneer depressed into both the deeper 80 and shallower depressions in the plate and the depressions that encircle the indicia, the whole dressed off to remove the surplus veneer;

Figure 6 is a similar sectional view to 85 Figure 5 with filler strips between the base plate and the veneer to assist in filling up the deeper recesses;

Figure 7 is a face view of a part of my design showing spacing strips placed between the blocks carrying the letters, to provide for variously spacing such blocks according to the widths of the spaces.

Figure 8 is an enlarged detail cross sectional view on the line 8—8 of Figure 2. 90 95

For convenience in understanding the article I will first describe the method aforesaid by which it is produced, which description will eventuate in the finished product.

I take a strip of metal preferably brass 100 indicated generally at 1 and by the action of dies or other means I form the face thereof with a comparatively deep depression indicated at 2 constituting a sort of channel running lengthwise the base. I also 105 fashion the plate with shallower depressions indicated at 3 which latter depressions border the deeper one designated 2. The

difference in the depth of the deeper and shallower depressions is preferably equal to the thickness of the metal blocks 4 on which are fashioned, preferably by treatment in dies, the letters, numerals or other indicia which will constitute the readable matter. These blocks 4 so configurated are of length just sufficient to snugly fit down within the deeper depression, with their ends fitting 10 against the ledge formed between the deeper and shallower depressions, such ledge being indicated at 5 in Figure 1. These indicia blocks are separate and independent of each other so that they may be positioned 15 in the deeper depression appropriately to be read and appear as may be desired.

Before placing and positioning the indicia blocks in such depression I overlay the same with adhesive material, preferably in 20 the form of a sheet or strip of celluloid indicated at 6. This strip I first saturate or in some cases immerse in acetone to cause the celluloid to reach a dissoluble state, so that when subjected to pressure and heat it 25 will entirely dissolve and leave a gummy or sticky mass to constitute an adhesive to hold the indicia blocks where adjusted in the deeper depression.

I then overlay both the indicia blocks and 30 their indicia as also the shallower depressions 3 with a like adhesive, or strip of celluloid 6^a treated as above stated.

I then take a piece of wood veneer, of size 35 about the same or a little larger than the metal base 1, and saturate it with, or subject it to a bath of, dissolved celluloid; or in some cases merely saturate it with a coating of acetone which will later attack the celluloid, whether in the form of a strip or 40 already dissolved, when the veneer has been treated to the pressure and heating steps. The veneer so conditioned is placed upon the adhesive that has been laid over the plate and indicia as above stated.

45 I then subject the whole composite structure to pressure, preferably bringing in contact with the wood veneer a pressure device in the nature of a platen having a flat pressure face. This pressure so applied 50 acts to force the veneer down into the shallower depression, into any uncovered portions of the deeper depression and into all of the recesses within and around the letters, numbers or other indicia. A pressure of 150 to 1000 pounds per square inch 55 maintained for from two to ten minutes and accompanied by heat ranging from 200 degrees F. to 250 degrees F. will accomplish this object.

60 It will be also understood that such pressure, particularly when accompanied by heat, will act to thoroughly unite the adhesive material with the metal base and the wood veneer. The adhesive, if in the form 65 of a celluloid sheet, more or less in a dis-

solving state, or if already in a fully dissolved state, acts admirably in completing the state of dissolution of this adhesive and in making a firm and permanent adherence between the metal base and the now inlaid 70 veneer.

After proceeding thus far there remains the final step of dressing-off as by grinding, abrading, or in a sense planing, the exposed veneer to remove the shattered portions and to make the veneer flush with the border of the base plate and the faces of the letters, numbers or indicia, which latter are at the same time polished so as to stand out in contrast with the wood veneer now inlaid 80 and forming a background or field.

Thus the method of producing my sign and the sign itself will be fully understood. It has the advantages of cheapness in production, durability and exceeding beauty or attractiveness.

So far I have let it be assumed that the depressions surrounding the letters, numbers or other design on the base plate would be sufficiently shallow to readily be filled with the veneer of wood. But there may be cases, as shown in Figure 9, where it will be desirable to employ fillers indicated at 7. These fillers are in the nature of strips, say 90 of metal, adapted to be laid in the deeper recesses to partially fill them so that the remainder of their depth can the more readily be filled and occupied by the veneer of wood. I will usually employ an adhesive, such as above set forth, between the bases 100 of the recesses and the filler strips 7 and between the latter and the veneer; the more perfectly to retain the veneer in the depressions.

The individual blocks 4 which carry the 105 letters, numbers or other indicia may be spaced apart as desired by placing between each two blocks a spacer or spacing strip 8 of one width or a spacer of another width as shown at 8^a in Figure 10.

110 It will also be understood that I desire to comprehend within my invention such modifications as may be necessary to adapt it to varying conditions and uses.

Having thus fully described my invention, what I claim as new and desire to secure by Letters Patent, is:

115 1. The herein described method of producing a sign, consisting in fabricating a base of metal having a depression for the 120 reception of raised indicia; in fabricating the raised indicia on separate blocks and inserting each block in such depression and relatively to the other blocks; in placing a wood veneer over the plate and the indicia; 125 in previously placing an adhesive to lie between the depression and the blocks and between the veneer and the plate and blocks; in subjecting the veneer to high flat pressure to force it into all of the exposed recesses 130

which it overlies; and in then subjecting the article to a dressing-off step to remove the surplus and shattered portions of the veneer and leave the remainder smooth and flush 5 with the indicia.

2. The herein described method of producing a sign consisting in fabricating a metal base with a deeper and a shallower depression; in applying an adhesive over such deeper depression; in fabricating readable raised indicia on separate blocks; in placing these blocks in the deeper depressions and in proper relation; in placing an adhesive over the indicia and their blocks 10 and the shallower depressions; in placing a sheet of wood veneer over the indicia, their blocks and the shallower depression and any exposed portions of the deeper depression; in subjecting such veneer to flat pressure sufficient in degree and point of time to sink the veneer into all of the exposed depressions; and in dressing-off the wood to remove the shattered portions and smooth the inlaid parts and present the indicia there- 15 through.

3. The herein described method of producing a sign consisting in fabricating a metal base with a deeper and a shallower depression; in fabricating raised indicia on individual blocks; in overlaying such deeper depression with a strip of celluloid in a soluble state; in placing said blocks in said depression over said celluloid; in placing over the shallower depressions, the blocks 20 and the indicia another sheet of celluloid in a dissoluble state; in saturating a sheet of wood veneer with a dissolving agent, such as acetone; in placing such sheet of veneer over the last-named sheet of celluloid; in subjecting the whole to flat pressure and heat sufficient to force the veneer into all 25 of the depressions exposed beneath it and to complete the dissolution of the celluloid; and in dressing-off the shattered portions of the veneer to leave the inlaid portions smooth and to expose the indicia.

4. The herein described method of producing a sign, consisting in fabricating a base of metal having a depression for the reception of raised indicia; in fabricating the indicia on separate blocks and inserting each block in such depression and relatively to the other blocks; in placing filler strips in the deeper depressions; in placing a wood veneer over the plate and its filler strips and over the indicia; in subjecting the veneer to a high flat pressure to force it into all of the exposed recesses and on the filler strips which it overlies; and in then subjecting the 30 article to a dressing-off step to remove the surplus and shattered portions of the veneer

and leave the remainder smooth and flush with the indicia.

5. The herein described article, consisting of a base of metal having a depression 65 therein, a series of blocks independently positioned in the depression, said blocks having indicia forming raised elements, an adhesive between the blocks and the depression, a veneer of wood seated in the depressions 70 between and within the indicia and in the plate with an adhesive between the veneer and such depressions, the face or upper surface of the article being dressed-off to give a finish to the veneer and to the exposed 75 indicia.

6. The herein described sign consisting of a metal base having a deeper and a shallower depression, an adhesive applied to the deeper depression; individual blocks 80 fitted and positioned within said deeper depression and over such adhesive, said blocks having indicia forming raised elements, another adhesive applied upon the upper surface of the plate and blocks, and a veneer 85 of wood seated in all of the depressions exposed to it, the whole being polished off on the face or upper surface.

7. The herein described sign consisting of a metal base having deeper and shallower 90 depressions, filler strips in the deeper depressions; individual blocks fitted and positioned within the deeper depressions, said blocks having indicia forming raised elements and a veneer of wood seated in all 95 of the depressions exposed to it including the depressions having the filler strips therein, the whole being polished off on the face or upper surface.

8. In the herein described sign, a metal 100 base having a depression therein, individual blocks fitted and positioned within said depression and having raised indicia; filler strips also in said depression at places not occupied by the indicia blocks, and a veneer 105 of wood seated in said depression at places between the indicia and in so much of the depth of the depression as not occupied by the filler strips.

9. In the herein described sign, a metal 110 base having a depression in one face thereof, individual blocks fitted in such depression and having raised indicia; individual spacing strips between the indicia blocks to properly position them; filler strips in parts of 115 the depression not occupied by said blocks, and a veneer of wood seated in the depression at places adjacent the indicia and over the spacing strips and over the filler strips.

In testimony whereof, I affix my signature.
FREDRICK H. AULD.
